UNITED STATES PATENT OFFICE

KENT W. BARTLETT, OF CHICAGO, ILLINOIS, ASSIGNOR TO JENKINS PETROLEUM PROCESS COMPANY, OF CHICAGO, ILLINOIS, A CORPORATION OF WISCONSIN

TREATMENT OF HYDROCARBON DEPHLEGMATION PRODUCTS

Application filed November 1, 1929. Serial No. 404,139.

My invention relates to a process and means for treatment of hydrocarbon dephlegmation products, and particularly to such products intermediately produced in the cracking treatment of petroleum hydrocarbons.

In a known method of cracking petroleum hydrocarbons, the cracked and partially cracked vapor initially produced is subjected to dephlegmation, the low boiling point, desirable fractions eliminated and condensed exterior to the cracking zone, and the high boiling point fractions returned thereto admixed with other hydrocarbons of higher boiling point for further cracking treatment. In a known variation of the above process dephlegmation is aided by directly contacting the initially produced cracked and partially cracked vapor with hydrocarbons of higher boiling point, the composite reflux condensate thus obtained containing the heavier fractions of the initially cracked vapor and added hydrocarbons.

Where a commingled or composite reflux, obtained as above described, is of a boiling range substantially higher than derived from cracked and partially cracked vapor, and particularly where such reflux comprises in part a substantial quantity of residual hydrocarbons, its introduction to a cracking zone is productive of objectionable carbon deposits therein.

I have discovered in cracking processes of the above type that liability of formation of objectionable carbon deposit can be greatly reduced, and the yield of desirable light hydrocarbons increased, by maintaining the final boiling point of the admixed or composite reflux condensate substantially equal to that portion of such condensate derived from the cracked and partially cracked vapor.

It is a general object of the invention to provide for a method of treatment of admixed or composite reflux condensate intermediately produced in the cracking treatment of hydrocarbons, wherein the final boiling point of such condensate shall be substantially equal to that portion of such con-

densate initially derived from such cracking treatment.

A corollary general object of the invention is to provide for a method of treatment of admixed or composite reflux condensate intermediately produced in part, in the cracking treatment of hydrocarbons, wherein the final boiling point of such condensate shall indicate absence of hydrocarbons of a heavy residual nature.

Another general object of the invention is to provide for a method of treatment of admixed or composite reflux condensate intermediately produced in part, in the cracking treatment of hydrocarbons and intended for direct admission to a cracking zone; wherein the carbon-forming tendency of such condensate in said cracking zone shall be reduced and the yield of desirable hydrocarbons increased.

In a cracking process where a raw base, such as crude petroleum, reduced crude, residuum and the like, is subjected to cracking conditions of heat and pressure, an important object of the invention is to provide for a method of treatment wherein a composite distillate, selectively dephlegmated from commingled cracked, partially cracked and natural distillate vapor, is intermediately produced from such raw base; the cracked and partially cracked vapor from said cracking treatment subjected to dephlegmation; the lighter desirable products obtained thereby eliminated and condensed exterior to the cracking zone; and the heavier reflux returned thereto for further cracking treatment admixed with said intermediately produced composite distillate.

In a cracking process, where crude petroleum, reduced crude, residuum or the like is the raw base, a specific purpose of the invention is to provide a method of treatment wherein a composite distillate, selectively dephlegmated from commingled cracked, partially cracked, and natural distillate vapor derived from said raw base, is initially subjected to cracking conditions of heat and pressure; the cracked and partially cracked vapors produced thereby subjected to dephlegmation; the lighter desirable products

100

eliminated and condensed exterior to the cracking zone, and the heavier reflux returned thereto for further cracking treatment admixed with an additional quantity of 5 said composite distillate.

In a cracking process wherein a composite petroleum distillate, selectively dephlegmated from commingled cracked, partially cracked, and natural distillate vapor serves 10 as cracking stock, an important purpose of the invention is to provide a method of treatment wherein the cracked and partially cracked vapor produced by such cracking process is subjected to dephlegmation; the 15 lighter products obtained thereby eliminated and condensed exterior to the cracking means, and the heavier reflux returned thereto for further cracking treatment admixed with an additional quantity of said composite 20 charging stock.

In cyclic cracking treatment where a finely divided mineral adsorbent, such as lime, is employed in dispersed circulation throughout an oil undergoing such cracking treatment in 25 a still of well known type, a more specific purpose of the invention is to provide for a method of treatment of commingled or composite reflux condensate, intermediately produced in part by said cracking treatment and 30 intended for direct subjection thereto, wherein the quantity of lime necessary for adsorption of carbon producing substance shall be reduced, and the yield of desirable hydrocarbons increased.

35 My process is applicable in its broadest scope to any liquid hydrocarbon amenable to cracking that remains substantially liquid under the cracking conditions employed, generates cracked vapor, and returns a reflux for 40 further cracking treatment. Under such conditions, I either admix with the reflux stream a hydrocarbon whose lower distillation range is substantially equal to that of the reflux produced from the cracked and partially cracked vapor, or more preferably I 45 commingle with the cracked and partially cracked vapor, a hydrocarbon of such distillation range as to permit proper dephlegmation of the initially cracked vapor, and 50 produce at the same time a composite reflux of substantially the same final boiling point, as the reflux fraction derived from the initially cracked vapor; accomplishing such objective and the previously enumerated advantages of less tendency for carbon deposition 55 and increase in production in desirable light hydrocarbons, by preferably employing for admixing or commingling purposes, a selective distillate hydrocarbon permitting of 60 the specified boiling point limitation.

In the application of my invention to a cracking process where crude petroleum, reduced crude, residuum or the like, is the raw base, while the cracking zone may be initially charged with such base and cracking con-

ditions of heat and pressure imposed thereon, I intermediately produce from said base a composite distillate for subsequent subjection to actual cracking conditions rather than the raw base. I obtain such composite 70 distillate by selectively dephlegmating and condensing exterior to the cracking zone, the commingled vapors of recycle stock and natural distillate, obtained through evaporation under reduced pressure by known means of 75 a portion of the cracking stock, and by distillation of the raw base respectively.

The cracked and partially cracked vapor produced under cracking treatment, is either 80 separately dephlegmated and its reflux condensate returned to the cracking zone, admixed with composite distillate of the nature described, or preferably the cracked vapor is commingled with said composite distillate during dephlegmation, and the resultant reflux condensate returned to the cracking zone for further treatment; the desirable light hydrocarbons or crude gasoline vapor being 85 eliminated in either case, and condensed exterior to the dephlegmating zone; or subjected to further treatment as desired.

The residuums respectively obtained as 90 end products of cracking and natural distillation contain varying quantities of sediment in suspension, such as free carbon and highly polymerized hydrocarbons. Upon commingling such residuum to produce a composite fuel oil, the sediment content thereof may remain substantially unchanged, become reduced on account of internal intersolubilities, 100 or initially increased over the weighted average of its components, due to therein obtaining colloidal hydrocarbon decomposition products assuming a noncolloidal form with attendant precipitation from solution. 105

Where suspended material, including precipitate as above formed, freely settles upon stagnation, a supernatent marine fuel oil is obtained of marketable B. X. specification; but if decomposition products remain in suspension, and especially where initially produced pressure distillate or crude gasoline contains impurities causing discoloration upon exposure to light, I provide a method of treatment wherein the sediment content of any residuum may be reduced to a negligible amount, and the effect of the objectionable impurities in the crude pressure distillate nullified, by admixing such residuum with a quantity of previously, sulphuric acid treated, pressure distillate, sufficient to increase the specific gravity differential between solution and sediment to effect settling of the latter upon stagnation; eliminating the settled material; dephlegmatively distilling 115 the supernatent liquid, recovering thereby gasoline free from products affected by exposure to light, and a final residuum or marine fuel oil substantially sediment free, of 120 minimum marketable B. X. content. 130

In order that the different phases of my invention will be clearly comprehended, reference will be made to the accompanying drawing essentially diagrammatic in nature, embodying one form of device that may be employed, but it is to be understood that such form of apparatus is illustrative only, and by no means defines the limits of my invention.

10 The drawing shows a diagrammatic sectional elevation of apparatus designed for carrying out my approved methods, where 1 represents a pressure cracking still of well known type, comprising a horizontal cylindrical drum 2, superimposed over front and rear sluiceways 3 and 4, supraadjacent to front and rear cross drums 5 and 6, respectively; the latter being connected by the tube bank 7. Circulation of the still contents is 15 effected by the propeller 8, driving means not shown. The still is to be considered as provided with the usual accessories, such as pressure gauges, thermometers, pyrometers and level gauges and mounted over a heating 20 furnace of standard design.

The vapor line 9 and reflux line 10 are in unrestricted connection with the baffle tower 11, indirect charging of the cracking zone, including introduction of adsorbent, being 25 effected through the charging line 12, having connection to reflux line 10 by branch line 10', as controlled by valve 10''; or through the baffle tower 11 with discharge thereto controlled at selective levels by the 30 valves 13, 13' and 13''. The secondary vapor line 14 extends from the top of the baffle tower 11 to the bubble tower 31, valve 15 serving to maintain any desired pressure on the cracking zone. The cracking zone discharge line 16, controlled by release valve 17, connects with the low pressure vapor separator 18, from which in turn the recycle stock vapor line 19 leads to the composite dephlegmating tower 20. The line 20 21 serves as a fuel discharge to the fuel settler 22, from the bottom of which suspended matter may be drawn off by valve 23; line 24 serving to carry off the supernatent relatively clear fuel to the cracked fuel oil tank 25.

In the simplest application of my invention to a cracking process, wherein the purpose is reduction of liability towards formation of objectionable carbon deposit, and increase in desirable light hydrocarbons, it may be assumed for example, that a crude pressure distillate of 500° F. end point is being released from the baffle tower 11 under 140 lbs. pressure, through the line 14, as controlled by the valve 15; and that a reflux stream of say 740° F. final boiling point, derived from the cracked, partially cracked, and entrained uncracked vapor entering the baffle tower through vapor line 9, is being returned to the drum 2, through reflux line

10; the reacting charge in the still being in this instance a heavy gas oil of 775° F. end point. To attain my objectives, I introduce by the line 12, either through the branch line 10' and reflux line 10, or preferably through the baffle tower 11, such charging stock that the mixed or composite reflux finally entering the still through line 10, will possess a final boiling point substantially equal to the reflux fraction derived from the vapors entering the tower through line 9; the selective discharge levels in baffle tower 11 allowing a considerable intermediate distillation range in the composition of charging stock when introduced at such points, and still permitting the final boiling point limitation of the composite reflux.

Where the still contents have been long subjected to cracking conditions, or where such charge contains natural fractions of a residual nature, the concentration of carbon-forming substance and the tendency towards objectionable deposits may be considerably reduced, accompanied by a corresponding increase in production of desirable light hydrocarbons, by introducing as charging stock a material not only acceptable from a distillation range, but essentially of distillate composition. Where the material undergoing cracking is decidedly of a residual nature, or where the cracking conditions of heat and pressure are severe, I find it best to employ as a charging stock, a carefully dephlegmated composite distillate from which all heavy residual fractions have been removed by prior distillation.

In the adaptation of the invention to cracking such raw stock as crude, reduced crude, residuum or the like, while such material may be directly employed as an initial charge in the cracking zone, I preferably first prepare from such raw stock for said initial subjection to cracking conditions, a selective natural primary distillate fraction, and subsequently continuously charge the cracking zone with a composite selective distillate fraction, dephlegmated from the commingled vapors of recycle stock and natural distillate intermediately produced.

In preparing such primary natural distillate charging stock from a raw base, which for example, will be considered as reduced crude of 26.8 A. P. I. gravity, the high pressure pump 26, operated by any suitable means, takes suction by line 27 from the raw base tank 28, discharging the reduced crude, under say 145 lbs. pressure by line 29, to the heat exchanging and trim coil 30, located in the top of the bubble tower 31, and thence passes by line 32 to the heat exchanger 33, in the base of the reboiler section 34. From the latter, the reduced crude passing through line 35, is forced to a greater or lesser degree through the heat exchanging and trim coil 36, as controlled by the valves 37, 37' and

37", and thence by line 38 to the tube still 39, heated by the furnace 40, which may if desired, be located anterior or posterior to the main cracking unit, supplying heating means thereto or receiving heat efflux therefrom, respectively.

The tube still 39 is so constructed of several thousand feet of continuous coil on well known lines, that the hot raw stock issuing therefrom by line 41, as controlled by valve 41', will enter the low pressure raw stock vapor separator 42, at such temperature and under such pressure, which released in said separator, will cause without occurrence of substantial cracking, a predetermined percentage separation therein of the lighter natural distillate fractions from the natural high boiling point residuum content; the latter flowing through line 43 to the straight run fuel oil tank 44, and the former passing off through the vapor line 45 to the composite dephlegmating tower 20. In the example chosen, the hot reduced crude will enter the low pressure raw stock vapor separator at a temperature, of say 825° F., and at a pressure of 35 lbs., which pressure will be substantially dissipated in the low pressure separator 42; resulting in the production of say 80% of 36 A. P. I. gravity distillate vapor, and 20% straight run fuel oil of 9 A. P. I. gravity.

The greater proportion of the vapor passing into the composite dephlegmating tower 20, initially at least, is condensed by the cooling action of the raw stock passing through the exchanging coil 36. Such condensed vapor drops to the reboiler section 34, where a substantially constant liquid level is maintained by the float control apparatus 46 and balanced valve 46'; the excess of condensate flowing by line 47 to the make-up or overflow tank 48, a direct discharge of condensate from the reboiler section being afforded by line 49 to the high pressure hot oil pump 50, which is also connected by the suction line 51 to tanks 48 and 28, as controlled by valves 48' and 28' respectively; so that practically any desired combination of distillate on raw stock may be employed as primary or emergency cracking material.

In preferred operation, the hot primary distillate cracking stock is charged by the hot oil pump 50, to the cracking still 1 through line 12 in the manner previously described, until a sufficient quantity of material has accumulated in the drum 2 to warrant firing the still, when the flow of charging stock is shut off for the time being and allowed to accumulate in the make-up tank 48. When cracking conditions have been imposed on still 1, propeller 8 having been started in the meantime, cracked vapor is allowed to release through line 14 as controlled by valve 15, to the bubble tower 31. The high pressure hot oil charging pump 50 is again start-

ed and continuous feed, including a predetermined quantity of lime introduced into the charging line 12 by auxiliary means not shown, thereafter maintained; a sufficient quantity of the reacting still contents being 70 continuously withdrawn in the meantime through line 16 to the low pressure vapor separator 18, as to maintain a substantially constant level in the drum 2.

Upon reduction in pressure on the withdrawn material in the vapor separator, a separation occurs therein where a vapor fraction, consisting of cracked and partially cracked material, commonly termed recycle stock, escapes through the line 19 to the composite dephlegmating tower 20, where it commingles with the natural distillate vapor derived from the raw stock; the condensed dephlegmated vapors now dropping to the reboiler section 34, being a composite condensate of cracked, partially cracked and natural distillate which now becomes the actual cracking stock charged to the still 1.

With the rise in temperature attendant upon the additional amount of vapor discharged into tower 20 and increased reboiling effect, the lightest vapors are no longer condensed, resulting in a light recycle stock being distilled off from a selective level through line 52, such vapor being condensed by cooling coil 53, the condensate thence flowing by line 54 to the light recycle stock tank 55, from which it is removed through suction line 56 by pump 57 and discharged into the bubble tower 31 by line 58; an appreciable amount of heavy crude gasoline being recovered thereby.

The dephlegmated crude gasoline vapor leaves the bubble tower 31 by line 59, is condensed by coil 60, and thence flows by line 61 to the gasoline tank 62; the reflux bubble tower bottoms flowing by line 63 through cooling coil 63', and thence by line 64 to the bubble tower bottoms tank 65, from which it may be returned to the cracking system, or eliminated as may be desired.

The cracked fuel oil separated in the low pressure vapor separator 18, is discharged therefrom together with its lime content to the fuel oil settler 22, from which the supernatent fuel flows by line 24 to the cracked fuel oil tank 25; the material settled out in settler 22 being eliminated from the system through valve 23. Where the supernatent relatively settled fuel does not meet a predetermined market specification, such as for example 0.5% of suspended matter, such fuel may be united with a portion of the straight run product; the pump 66 taking suction by line 67 from tanks 44 and 25, as controlled by valves 44' and 25' respectively, serving for such purpose and discharging the mixed fuel by line 68 to the conical bottom mixing tank of standard design 69, provided with a 130

draw off valve 69' for removing sedimentary material, and fitted with any well known means for effecting intimate admixture of contents; such as a compressed air line or 5 mechanical agitation device.

Where such admixed fuel does not meet the required specification, either through inter-solubility or by precipitation of additional sedimentary material, and especially where 10 the crude gasoline released from bubble tower 31 contains impurities causing discoloration on exposure to light, such gasoline is conducted by means of line 70, from tank 62, through the agency of pump 71, to the conical 15 bottom treating agitator 72, of well known design, provided with a waste draw-off valve 72', run down valve 73, and the usual means (not shown) for introducing acid, alkali, water, and securing intimate admixture and 20 agitation of contents; or such form of apparatus may be replaced by any known type of continuous treating means. Sulphuric acid of sufficient strength to nullify the action of compounds causing discoloration of 25 said gasoline on exposure to light is employed in either case, and the spent acid eliminated from the system; in the accompanying illustration through valve 72'. The treated gasoline is discharged through valve 73 and 30 74 to the mixing agitator 69, sufficient gasoline being employed to raise the A. P. I. gravity of the resultant mixture to a point conducive 35 to the separation of suspended material, say to 16 A. P. I. gravity.

After thorough incorporation and settling of the agitator contents, the settled material is eliminated through valve 69', the supernatent solution withdrawn through suction line 75 by pump 76, and discharged through line 77 to the bubble tower 78, where the mixture of fuel oil and gasoline is dephlegmatically distilled through the agency of super-heated steam, introduced through the dry coil 79; or if desired, the solution of gasoline and fuel oil may be heated to a flashing temperature in a tube still or other suitable means, placed anterior to the bubble tower 78, and discharging therein.

The gasoline vapor dephlegmated in tower 78 discharges through vapor line 80, is condensed in coil 81, and flows thence by line 82 to the gasoline tank 83, from which it may be withdrawn from the system as a finished 50 product by suitable means (not shown), or subjected to further treatment, if desired. Finished specification fuel oil is eliminated through valve 84, line 85, and accumulates in tank 86, from which it may be removed by 55 any suitable means.

The application of my process is not limited to the apparatus illustrated and described in the foregoing specification, neither am I bound by the temperatures, pressures, gravities 60 and other constants disclosed therein,

which are to be considered as illustrative examples only of the process, and what I consider new and desire to protect by Letters Patent is:

1. A process for clarifying residual hydro-carbon oils which have been subjected to a cracking reaction in the presence of hydrated lime and which still contain suspended and colloidal hydrated lime associated with carbon from the cracking reaction, which comprises settling and removing from said residual hydrocarbon oils a portion of the suspended hydrated lime associated with carbon, 70 distilling and separating additional hydrocarbon oils into a vapor portion and a residual 75 portion containing substantially no suspended sediment, mixing said residual portion containing substantially no suspended sediment with said residual hydrocarbon oils to coagulate said colloidal hydrated lime, 80 settling and removing from the mixture of hydrocarbon oils suspended and coagulated hydrated lime associated with carbon whereby a composite residual fuel oil is produced 85 having a negligible sediment content. 90

2. A process for clarifying residual hydro-carbon oils which have been subjected to a cracking reaction in the presence of hydrated lime and which still contain suspended and colloidal hydrated lime associated with carbon from the cracking reaction, which comprises settling and removing from said residual hydrocarbon oils a portion of the suspended hydrated lime associated with carbon, 95 distilling and separating additional hydrocarbon oils into a vapor portion and a residual portion containing substantially no suspended sediment, mixing said residual portion containing substantially no suspended sediment with said residual hydrocarbon oils to coagulate said colloidal hydrated lime, 100 introducing into the mixture of hydrocarbon oils a hydrocarbon distillate to sufficiently increase the specific gravity differential between the mixture of hydrocarbon oils thus produced and the therein suspended and coagulated hydrated lime associated with carbon to effect easy removal of the latter from suspension by subsequent settling, settling and removing from said mixture of hydrocarbon oils suspended and coagulated hydrated lime associated with carbon, distilling and recovering from said mixture of hydrocarbon oils said hydrocarbon distillate whereby a composite residual fuel oil is produced 105 110

115 having a negligible sediment content.

3. A process for clarifying residual hydro-carbon oils which have been subjected to a cracking reaction in the presence of hydrated lime and which still contain suspended and colloidal hydrated lime associated with carbon from the cracking reaction, which comprises settling and removing from said residual hydrocarbon oils a portion of the suspended hydrated lime associated with carbon, 120 125 130

distilling and separating additional hydrocarbon oils into a vapor portion and a residual portion containing substantially no suspended sediment, mixing said residual portion containing substantially no suspended sediment with said residual hydrocarbon oils to coagulate said colloidal hydrated lime, treating a cracked hydrocarbon distillate with sulphuric acid to produce a photo-chemical effect therein, introducing into the mixture of hydrocarbon oils the treated hydrocarbon distillate to sufficiently increase the specific gravity differential between the mixture of hydrocarbon oils thus produced and the therein suspended and coagulated hydrated lime associated with carbon to effect easy removal of the latter from suspension by subsequent settling, settling and removing from said mixture of hydrocarbon oils suspended and coagulated hydrated lime associated with carbon, distilling and recovering from said mixture of hydrocarbon oils said hydrocarbon distillate separated from impurities causing discoloration upon exposure to light whereby a composite residual fuel oil is produced having a negligible sediment content and retaining said impurities in solution.

4. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with hot vapors flashed and separated from said withdrawn oils to form a composite distillate, fractionally condensing and separating out heavier fractions from said composite distillate to form a composite condensate, and introducing said composite condensate into the mass of hydrocarbon oils subjected to said cracking temperature and pressure heretofore mentioned.

5. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled

from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, and introducing said composite condensate into the mass of hydrocarbon oils subjected to said cracking temperature and pressure heretofore mentioned. 70

6. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, reducing pressure on the oils so withdrawn while the latter are in a heated condition to flash a portion thereof into hot vapors, separating said vapors from unvaporized residual oils, 80 heating additional hydrocarbon oils to effect a distillation of vapors therefrom, separating vapors so distilled from the unvaporized portion of said additional hydrocarbon oils, mixing out of contact with unvaporized oils, 85 vapors so distilled and separated with hot vapors flashed and separated from said withdrawn oils to form a composite distillate, fractionally condensing and separating out heavier fractions from said composite distillate to form a composite condensate, introducing said composite condensate into said reflux condensate portion to form a mixture of oils, and introducing the mixture of oils thus formed into the mass of hydrocarbon 90 oils subjected to said cracking temperature and pressure heretofore mentioned. 95

7. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, introducing said compos- 100 105 110 115 120 125

ite condensate into said reflux condensate portion to form a mixture of oils, and introducing the mixture of oils thus formed into the mass of hydrocarbon oils subjected to said cracking temperature and pressure heretofore mentioned.

8. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with hot vapors flashed and separated from said withdrawn oils to form a composite distillate, fractionally condensing and separating out heavier fractions from said composite distillate to form a composite condensate, introducing said composite condensate into direct physical contact with vapors evolved from said mass of hydrocarbon oils to form a mixture of oils and vapors, fractionally condensing and separating the mixture of oils and vapors thus formed into a vapor portion containing gasoline fractions and a composite condensate portion, and introducing said composite condensate portion into the mass of hydrocarbon oils subjected to said cracking temperature and pressure heretofore mentioned.

9. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate into direct physical contact with vapors evolved from said mass of hydrocarbon oils to form a mixture of oils and vapors, fractionally condensing and separating the mixture of oils and vapors thus formed into a

vapor portion containing gasoline fractions and a composite condensate portion, and introducing said composite condensate portion into the mass of hydrocarbon oils subjected to said cracking temperature and pressure heretofore mentioned.

10. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate having such distillation characteristics as to subsequently produce upon admixture with said reflux condensate portion a mixture of oils having a final boiling point closely approximating that of said reflux condensate portion, introducing said composite condensate into said reflux condensate portion to form a mixture of oils having a final boiling point closely approximating that of said reflux condensate portion, and introducing the mixture of oils thus formed into the mass of hydrocarbon oils subjected to said cracking temperature and pressure heretofore mentioned.

11. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with hot vapors flashed and separated from said withdrawn oils to form a composite distillate, fractionally condensing and separating out heavier fractions from said composite distil-

- late to form a composite condensate having such distillation characteristics as to subsequently produce upon admixture with said reflux condensate portion a mixture of oils 5 having a final boiling point closely approximating that of said reflux condensate portion, introducing said composite condensate into said reflux condensate portion to form a mixture of oils having a final boiling point closely 10 approximating that of said reflux condensate portion, and introducing the mixture of oils thus formed into the mass of hydrocarbon oils subjected to said cracking temperature and pressure heretofore mentioned.
- 15 12. A process for clarifying residual hydrocarbon oils which have been subjected to a cracking reaction and which contain suspended carbon and semi-solid carbonaceous products from the cracking reaction, which 20 comprises distilling and separating additional hydrocarbon oils into a vapor portion and a residual portion containing substantially no suspended sediment, mixing said residual portion containing substantially no 25 suspended sediment with said residual hydrocarbon oils to coagulate said suspended carbon and semi-solid carbonaceous products from the cracking reaction, settling and removing from the mixture of hydrocarbon oils 30 thus formed suspended and coagulated carbon and semi-solid carbonaceous products from the cracking reaction whereby a composite residual fuel oil is produced having a negligible sediment content.
- 35 13. A process for clarifying residual hydrocarbon oils which have been subjected to a cracking reaction and which contain suspended carbon and semi-solid carbonaceous products from the cracking reaction, which 40 comprises distilling and separating additional hydrocarbon oils into a vapor portion and a residual portion containing substantially no 45 suspended sediment, mixing said residual portion containing substantially no suspended sediment with said residual hydrocarbon oils to coagulate said suspended carbon and semi-solid carbonaceous products from the cracking reaction, introducing into the mixture of hydrocarbon oils thus formed 50 a hydrocarbon distillate to sufficiently increase the specific gravity differential between the mixture of hydrocarbon oils thus produced and the therein suspended and coagulated hydrated lime associated with carbon to effect removal of the latter from suspension by subsequent settling, settling and removing from said mixture of hydrocarbon oils suspended and coagulated hydrated lime associated with carbon, and distilling and recovering from said mixture of hydrocarbon oils said hydrocarbon distillate whereby a composite residual fuel oil is produced having a negligible 55 sediment content.
- 60 14. A process for clarifying residual hydrocarbon oils which have been subjected to a cracking reaction in the presence of suspended and colloidal hydrated lime associated with carbon from the cracking reaction, which comprises distilling and separating additional hydrocarbon oils into a vapor portion and a residual portion containing substantially no suspended sediment, mixing said residual portion containing substantially no suspended sediment with said residual hydrocarbon oils to coagulate said colloidal hydrated lime, settling and removing from the mixture of hydrocarbon oils thus formed suspended and coagulated hydrated lime associated with carbon whereby a composite residual fuel oil is produced having a negligible sediment content. 70
- 75 15. A process for clarifying residual hydrocarbon oils which have been subjected to a cracking reaction in the presence of hydrated lime which still contain suspended and colloidal hydrated lime associated with carbon from the cracking reaction, which comprises distilling and separating additional hydrocarbon oils into a vapor portion and a residual portion containing substantially no suspended sediment, mixing said residual portion containing substantially no 80 suspended sediment with said residual hydrocarbon oils to coagulate said colloidal hydrated lime, introducing into the mixture of hydrocarbon oils thus formed a hydrocarbon distillate to sufficiently increase the specific gravity differential between the mixture of hydrocarbon oils thus produced and the therein suspended and coagulated hydrated lime associated with carbon to effect removal of the latter from suspension by subsequent settling, settling and removing from said mixture of hydrocarbon oils suspended and coagulated hydrated lime associated with carbon, and distilling and recovering from said mixture of hydrocarbon oils said hydrocarbon distillate whereby a composite residual fuel oil is produced having a negligible sediment content. 85
- 90 16. In testimony whereof I have affixed my signature.

DISCLAIMER

1,882,269.—*Kent W. Bartlett*, Chicago, Ill. TREATMENT OF HYDROCARBON DEPHLEGMATION PRODUCTS. Patent dated October 11, 1932. Disclaimer filed December 7, 1933, by the assignee, Jenkins Petroleum Process Company.

Hereby enters this disclaimer to claims 4, 5, 6 and 7 of the aforesaid Letters Patent which are in the following words, to wit:

“4. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with hot vapors flashed and separated from said withdrawn oils to form a composite distillate, fractionally condensing and separating out heavier fractions from said composite distillate to form a composite condensate, and introducing said composite condensate into the mass of hydrocarbon oils subjected to said cracking temperature and pressure heretofore mentioned.

“5. A process for the production of gasoline and other oils from hydrocarbon oils which comprises subjecting a mass of hydrocarbon oils to a cracking temperature under pressure to crack said oils and evolve vapors therefrom, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, and introducing said composite condensate into the mass of hydrocarbon oils subjected to said cracking temperature and pressure heretofore mentioned.

“6. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, reducing pressure on the oils so withdrawn while the latter are in a heated condition to flash a portion thereof into hot vapors, separating said vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils, vapors so distilled and separated with hot vapors flashed and separated from said withdrawn oils to form a composite distillate, fractionally condensing and separating out heavier fractions from said composite distillate to form a composite condensate, introducing said composite condensate into said reflux condensate portion to form a mixture of oils, and introducing the mixture of oils thus formed into the mass of hydrocarbon oils subjected to said cracking temperature and pressure heretofore mentioned.

“7. A process for the production of gasoline and other oils from hydrocarbon oils which comprises subjecting a mass of hydrocarbon oils to a cracking temperature under pressure to crack said oils and evolve vapors therefrom, separating said vapors into a vapor portion containing gasoline fractions and a reflux condensate portion, withdrawing residual oils from said mass of oils, effecting vaporization of a portion of the residual oils so withdrawn, separating evolved vapors from unvaporized residual oils, heating additional hydrocarbon oils to effect a distillation of vapors therefrom, separating vapors so distilled from the unvaporized portion of said additional hydrocarbon oils, mixing out of contact with unvaporized oils vapors so distilled and separated with vapors evolved and separated from said withdrawn oils to form a composite distillate, fractionally condensing and separating out heavier fractions from said composite distillate to form a composite condensate, introducing said composite condensate into said reflux condensate portion to form a mixture of oils, and introducing the mixture of oils thus formed into the mass of hydrocarbon oils subjected to said cracking temperature and pressure heretofore mentioned.”
